(57) **CLAIM**

The ornamental design for a tamper evidence container closure, as shown and described.

DESCRIPTION

FIG. 1 is a top perspective view of a tamper evidence container closure.

FIG. 2 is a bottom perspective view of the tamper evidence container closure shown in FIG. 1.

FIG. 3 is a front side view of the tamper evidence container closure shown in FIG. 1.

FIG. 4 is a bottom view of the tamper evidence container closure shown in FIG. 1.

FIG. 5 is a detail view taken within a portion “5” of the tamper evidence container closure shown in FIG. 3.

FIG. 6 is a cross-sectional view taken along line 6-6 of the portion “5” of the tamper evidence container closure shown in FIG. 5; and,

FIG. 7 is a cross-sectional view taken along line 7-7 of the portion “5” of the tamper evidence container closure shown in FIG. 5.

The dash-dash broken lines represent portions of the tamper evidence container closure that form no part of the claimed design. The dash-dot-dot broken lines represent boundaries of the enlarged views and form no part of the claimed design. Any surfaces inside the tamper evidence container closure form no part of the claimed design.
